Application August 11, 1944, Serial No. 549,108

9 Claims. (Cl. 140—112)

1

This invention relates to apparatus for making welded wire fabric, hereinafter referred to as fence, and more particularly to a machine of the general type shown in Perry Patent No. 813,823.

The Perry patent shows a fence making machine in which a plurality of parallel vertical strand wires are intermittently fed upwardly through the machine while a single horizontal cross wire is intermittently fed across the strand wires. The cross wire is cut periodically at one end of the machine to form a stay wire that is then transferred sideways into contact with the strand wires to which it is welded while the cross wire is again fed across the machine. The strand wires then move upwardly a distance corresponding to the desired distance between the stay wires, following which the next stay wire is welded to the strand wires in the same way as the previous stay wire. This machine is used extensively for making welded wire fence, but it has the disadvantage that only one stay wire at a time can be welded to the strand wires. The rate of production of the Perry machine can not be increased by merely doubling the number of cross wires and the mechanism that handles them, because his stay wire transfer mechanism would then interfere with feeding of the cross wires across the strand wires.

It is among the objects of this invention to provide a machine for making welded wire fence in which a plurality of stay wires are simultaneously welded to strand wires, in which new stay wires are formed as the preceding set is being welded to the strand wires, in which several stay wires can be formed and welded to the strand wires substantially as quickly as a single stay wire, and in which fence can be produced at a materially faster rate than heretofore.

The preferred embodiment of the invention is illustrated in the accompanying drawings in which Fig. 1 is a front view of our machine with the strand wire guide rollers omitted; Fig. 2 is a view of the left end of the machine; Fig. 3 is an enlarged fragmentary view of the right end; Fig. 4 is a still further enlarged fragmentary horizontal section taken on the line IV—IV of Fig. 3; Fig. 5 is an enlarged fragmentary rear view of one of the picker fingers and the supporting bar; Figs. 6, 7, and 8 are fragmentary vertical sections all taken on the line A—A of Fig. 1 but showing the stay wire transfer mechanism in three different positions; Fig. 9 is a fragmentary vertical section taken on the line IX—IX of Fig. 1; and Fig. 10 is a front view of the apparatus shown in Fig. 9.

2

Referring to Figs. 1, 2, and 3 of the drawings, the machine has a pair of end frames 1 and 2 that are rigidly connected in front by a long horizontal plate 3 provided on top with a dove tail rib 4. The end frames are connected centrally by horizontal beams 5 and 6. The tops of the end frames support a rotatable horizontal shaft 7 on which a plurality of grooved wheels 8 are rigidly mounted. These wheels are provided with radial lugs 9 (Fig. 2) spaced apart the same distance as the stay wires of the fence being made by this machine. Parallel strand wires 10 are led from coils rotatably mounted in front of the machine to grooved guide rollers journaled in the lower front part of the machine. These coils and rollers, which are of conventional form and well known, are not shown. The wires pass under the guide rollers and then straight up through the machine to wheels 8 over which they travel before passing down to a reel 11 journaled in brackets 12 projecting from the back of the end frames.

As shown in Fig. 2, the machine is driven by a belt 13 that extends around a pulley 14 supported by bracket 12 at the left end of the machine. This pulley carries a pinion 16 which meshes with another pinion 17 supported by the same bracket, and the second pinion drives a large gear 18 mounted on the projecting end of a horizontal shaft 19 which is journaled in bearings 21 in the lower rear portions of the two end frames. One of the spokes of this large gear is provided with a radial slot 22 in which the lower end of a vertical rod 23 is slidable. The upper end of the rod is pivotally connected to the outer end of an arm 24 the inner end of which is oscillatably mounted on the end of top shaft 7. This arm is provided with a spring-pressed pawl 26 for engaging a ratchet wheel 27 rigidly mounted on the top shaft. The ratchet wheel is prevented from rotating in a reverse direction by a spring-pressed dog 28 pivotally supported by the adjacent end frame. It will be seen that every time gear 18 makes a complete revolution, it oscillates arm 24 and thereby rotates the top shaft a few degrees to feed the strand wires ahead the necessary distance.

The top shaft also projects beyond the right hand end frame 2, and its projecting end has a ratchet wheel 30 rigidly mounted thereon, as shown in Fig. 3. Encircling this wheel is a loose pulley 31 that carries a spring-pressed pawl 32 which is engaged by the teeth of ratchet wheel 30 so that the pulley is turned by the wheel every time the top shaft is turned. Pulley 31 is connected by a belt 33 to another pulley 34 (Fig. 1)

rigidly mounted on the end of reel 11 at the back of the machine, whereby to drive the reel in order to wind thereon the fence that is made in this machine.

In order to produce the stay wires for the fence, a pair of vertically spaced horizontal cross wires are fed across the machine from left to right in the following manner. As shown in Fig. 2, the large gear 18 is operatively connected through bevel gears 36 and 37 to the rear end of a horizontal shaft 38 journaled in the lower part of end frame 1. Rigidly mounted on the front end of this shaft is a short arm 39 on the outer end of which a pawl 40 is pivotally mounted. One end of this pawl normally is urged by a spring into engagement with a ratchet wheel 41 rotatably mounted on the outer end of shaft 38. Rigidly connected to this ratchet wheel is a pinion 42 (Fig. 1) that meshes with a gear 43 rotatably supported by a bracket 44 projecting laterally from the end frame. Gear 43 drives another gear 46 also supported by the same bracket, while rigidly connected to the rear side of the second gear is a pinion 47 that meshes with another pinion 48 on the front end of a horizontal shaft 49 journaled on a pedestal bearing 51. The rear end of this shaft carries a bevel pinion 52 (Fig. 2) that meshes with a similar pinion 53 on the lower end of a vertical shaft 54 also supported by the pedestal bearing. The upper end of shaft 54 is journaled in a bearing 56 supported by a horizontal I-beam 57 the opposite ends of which are supported by end frame 1 and by the top of a vertical I-beam 58 resting on the machine foundation.

Rigidly mounted on vertical shaft 54 is a pair of large grooved feed rolls 60 that substantially engage a pair of smaller grooved feed rolls 61 in front of them. The smaller rolls are carried by arms 62 which are pivotally supported by brackets 63 projecting laterally from the vertical I-beam. Threaded through the outer ends of these arms are hand screws 64 that bear against the brackets for adjusting the pressure of the smaller rolls against the larger ones. The horizontal cross wires 65 and 66 are delivered to the two sets of feed rolls from reels and straightening mechanism (not shown), and are fed by the rolls across the machine in front of the vertical strand wires. Once during each revolution of arm 39 the projecting rear end of its pawl 40 strikes a stop 67 on the end frame and is thereby swung out of engagement with ratchet wheel 41 so that the ratchet stops rotating for a moment. This causes the feed rolls to stop, which means that the feed of the horizontal wires across the machine is intermittent.

The feed rolls deliver cross wires 65 and 66 to a pair of vertically spaced cutters that sever them every time their forward motion is interrupted, which, according to the timing of the machine, occurs every time the leading ends of the wires reach the opposite or right end of the machine. As shown in Figs. 9 and 10, the frame 71 of the two cutters is supported by and behind ribbed plate 3 close to the inside of end frame 1 of the machine. This cutter frame is provided with a vertical passage through it with a bar 72 slidably mounted therein. The bar has a pair of vertically spaced extensions 73 and 74 projecting rearwardly through slots in the frame. These projections are provided with horizontal openings which, in their normal lower positions, are in line with the cross wires that pass through them. Bar 72 is normally held in its lower position by a leaf spring 76 connected to the top of the cutter frame and

pressing down on top of the bar. One side of the cutter frame is provided with an opening into one side of its vertical passage, and the bar is provided with a transverse slot 78 beside that opening. Projecting into this slot is the lower end of a bell crank lever 79 that is pivotally supported by the cutter frame. The upper end of this lever is pivotally connected to the inner end of a link 81 that has its outer end pivotally connected to the upper front end of an actuating lever 82, as shown in Figs. 1 and 2. The central portion of lever 82 is pivotally mounted on the outside of end frame 1, and its lower end rides against the inner face of big gear 18 which is provided with a boss 83 for periodically swinging the lower end of the lever toward the end frame. This movement causes the lever to pull the link and thereby swing the lower end of bell crank 79 upwardly. This raises bar 72 by which the cross wires are lifted up against stationary knives 84 and 85 projecting downwardly and rearwardly from the cutter frame, whereby the wires are severed in order to produce stay wires 86 and 87 (Figs. 1, 6, 7, and 8) of predetermined length.

As the cross wires travel across the machine before they are cut, they are supported and guided by two vertically spaced rows of laterally spaced guide members through which the wires pass. These guides are mounted on the rear sides of a pair of parallel cross bars 90 and 91 supported at their opposite ends by inverted L-shape bars 92 the upper front ends of which are clamped to rib 4 of cross plate 3. A vertically spaced pair of these guide members is disposed in front of each strand wire (Fig. 1). As shown in Figs. 4 and 6, each guide includes a metal block 95 connected to the cross bar in front of it and provided with a wire-receiving slot 96 extending across its lower side. The bottom of this slot normally is closed by a jaw 97 having upright ears that are pivotally mounted on a pin 98 extending through the block. The jaw is urged toward its upper closed position by coil springs 99 behind it, but it can be swung downwardly away from the slot by pressing the wire in the slot downwardly against the jaw, thereby permitting the wire to be removed from the bottom of the slot.

The vertical strand wires travel across two vertically spaced rows of electrodes 101 supported behind them by beam 6. Directly opposite these electrodes and disposed in a vertical plane normally in front of the guide member slots 96 is another set of electrodes 102. Electricity is supplied to the two sets of electrodes in the usual manner through transformers 103 suspended from the electrodes. Each vertically spaced pair of front electrodes is carried by a block 104 supported by the rear end of a horizontal rod 106 slidably mounted in the front and rear portions of a horizontal beam 107. The rod is urged rearwardly by an encircling coil spring 108 compressed between the front portion of the beam and a shoulder on the rod. Rearward movement of the rods is limited by stop nuts 109 threaded on their outer ends and normally engaging the front of the beam. The opposite ends of this beam are slidably mounted in horizontal guideways 111 (Fig. 1) in the front portions of the end frames of the machine. The beam is reciprocated in these guideways, in order to move the front set of electrodes toward and away from the rear set, by a pair of horizontal rods 112 the front ends of which are connected to the ends of the beam. The rear ends of these rods are pivotally connected to the central portions of verti-

cal rocker arms 113 that are pivotally connected at their upper ends to the inside of the adjacent end frames, as shown in Fig. 3. The lower portions of the rocker arms are bifurcated and carry rollers 114 that engage cams 116 rigidly mounted on bottom shaft 19. Rotation of these two cams therefore swings the lower ends of the rocker arms back and forth and thereby reciprocates beam 107 in the end frames of the machine.

As soon as a pair of stay wires has been formed in front of the strand wires by cutting the two cross wires, which stopped just long enough to be cut, the stay wires are quickly removed from the guide members and transferred to the strand wires to which they are welded. By the time this has occurred and the strand wires have been moved upwardly by wheels 8, a new set of stay wires is ready to be welded to the strand wires. Handling of the stay wires, just before the welding operation, is accomplished by what is known as a picker mechanism. The frame of this mechanism is formed by a pair of vertically spaced horizontal rods 129 extending across the machine in front of the strand wires above and below the guide members with the ends of the rods rigidly mounted in a pair of vertical bars 121, as shown in Figs. 1, 4, 9, and 10. Each of these bars is provided near its top and bottom with pins 122 projecting laterally through a pair of slots 123 in a vertical guide plate 124 near the adjacent end frame of the machine. These guide plates are supported by brackets 126 and 127 projecting forward from the end frames and beam 5, respectively, the guide plates being connected to the brackets by pins 128 projecting laterally from the top and bottom of the plates into short horizontal slots 129 in the brackets. The left hand guide plate is provided with notches 130 through which the cross wires extend.

The guide plate slots 123 have vertical upper portions and rearwardly and downwardly inclined lower portions. Pins 122 are moved up and down in these slots by levers 131 that are pivotally connected to the inside of the end frames. The front ends of these levers are pivotally connected to forked links 132 oscillatably mounted on the upper rod 120 of the picker mechanism next to the end bars. The rear ends of the levers are operatively connected by vertical rods 133 to eccentrics 134 (Figs. 1 and 3) mounted on bottom shaft 19 adjacent the rocker cams.

Guide plates 124 are moved back and forth in bracket slots 129 by means of short horizontal rods 136 projecting from their rear edges. Each of these rods is slidably mounted in a pair of spaced brackets 137 projecting inwardly from the adjacent end frame of the machine. The central portion of the rod is reduced in diameter to provide shoulders near its ends between which and a sleeve 138, slidably mounted on the center of the rod, a pair of coil springs 139 are mounted. The ends of the sleeve are encircled by integral collars between which the sleeve is straddled by the bifurcated lower end of a bell crank lever 141. This lever is pivotally connected to the adjacent end frame of the machine. The upper end of the lever is connected to the upper end of an inclined rod 142 that terminates in a bifurcated member 143 straddling bottom shaft 19 beside the adjacent rocker cam 116 (Figs. 1 and 3). Mounted on the side of this member is a cam follower roller 144 that engages a cam 145 fastened to the bottom shaft. When rod 142 is reciprocated by cam 145 lever 141 is oscil-

lated and its lower end therefore pushes against one of the collars on sleeve 138. This pressure is transmitted through the adjoining spring 139 to the rod 136 which is thereby moved either forward or backward to move the adjoining guide plate 124 in the same direction.

Connected to picker frame rods 120 at points midway between the strand wires are the ends of vertical picker bars 150. As shown in Figs. 10 to 8, each of these bars is provided in one side with a pair of vertically spaced L-shape recesses 151, at one side of the rear end of each of which there is a projection of the bar to which a picker finger 152 is pivotally connected. These fingers are spaced apart the same distance as the stay wires. The rear portion of each finger below its pivot is provided with a notch that cooperates with a similar notch in the adjoining portion of the bar for receiving a stay wire. 15 Each finger also has its front end urged upwardly by a coil spring 154 connected thereto and to the upper end of the recess. When the picker mechanism is in its upper position the upper row of these picker fingers is above the top stay wire and the lower row of fingers is between the two stay wires. When levers 131 move the picker bars downwardly, the stay wires are gripped by the fingers and forced out of the bottoms of slots 96 in the guide members. After the stay wires have been thus freed from the guides they are moved downwardly and rearwardly into contact with the strand wires in positions directly in front of the rear electrodes. As this occurs, the front electrodes are moved back against the stay wires to hold them against the strand wires, as shown in Fig. 7, while guide plates 124 are moved forward by rods 136 to cause the picker fingers to be released from the stay wires. As soon as the picker fingers leave the stay wires, welding takes place at the points of intersection of the stay and strand wires.

After the guide plates and the rest of the picker mechanism have been moved forward away from the welded wires, levers 131 raise end bars 121 in slots 123 of the guide plates to elevate the picker fingers above the new stay wires that have been fed into the guide members in the meantime. Rods 136 then move the guide plates back to their rear position so that the 45 picker fingers can again be lowered to engage the new stay wires and transfer them to the strand wires for welding. Fig. 8 shows the empty picker fingers in their forward position about half way between their upper and lower 50 positions as they are being raised. While this is happening the electrodes are separated and the strand wires with the stay wires that have been welded to them are moved upwardly a predetermined distance.

60 The operation of this machine will now be reviewed. As strand wires 10 are pulled upwardly across rear electrodes 101 by means of wheels 8, the cross wires 65 and 66 are fed across the machine in front of the strand wires by means of feed rolls 60 and 61. These cross wires pass through the openings in cutter bar extensions 73 and 74 and through slots 96 in the two rows of gripping members. When the leading ends of the cross wires reach the opposite end of the machine, the pawl 40 on continuously rotating shaft 38 strikes stop 67 (Fig. 1) by which it is moved out of engagement with ratchet wheel 41. This stops the rotation of the feed rolls for a moment, and while the cross wires are stationary the lower end of lever 82 is struck by boss 83

(Fig. 2) on large gear 18, thereby causing the upper end of the lever to pull cutter lever 19 to the left. The lower end of the cutter lever is therefore moved upwardly and, by reason of its projection into slot 78 in cutter bar 72, it raises the bar and its extensions 73 and 74 and thereby forces the cross wires against knives 84 and 85 by which the wires are cut to form stay wires 86 and 87.

While the cutter bar is returning to its original position, levers 131 start to move the picker fingers 152 downwardly from their Fig. 6 position. The path of movement of the fingers is determined and controlled by the slots 123 in guide plates 124 at the opposite ends of the machine, because pins 122 on the end bars 121 of the picker frame slide in those slots. The downwardly moving picker fingers snap onto the two stay wires supported by the guide members and then force them down out of slots 96 in those members by pressing the wires down against jaws 97 which are thereby swung down and away from the slots. As soon as this has occurred, pawl 40 again engages ratchet wheel 41 which causes the feed rolls to resume feeding of the cross wires across the machine and through the empty guide members. While this is going on, the picker fingers continue to move the stay wires downwardly and then rearwardly until the stay wires engage the strand wires in front of rear electrodes 101, as shown in Fig. 7. In the meantime, the strand wires have stopped moving, due to large gear 18 reaching a position in which it is moving arm 24 upwardly so that pawl 26 slides over the teeth of ratchet wheel 27 instead of turning the wheel.

By the time the stay wires have engaged the strand wires, the front electrodes 102 have been moved toward the rear electrodes by means of cross beam 107 which is reciprocated by the cam actuated rocker arms 113. The two sets of wires are gripped between the two pairs of electrodes and held tightly together, whereupon guide plates 124 are moved forward by short rods 136 which are actuated by cranks 141 and cam actuated rods 142. The picker frame is carried forward with the guide plates, the picker fingers opening and releasing the stay wires as they are pulled away from those wires. As soon as the fingers are freed from the stay wires, electric current is supplied to the electrodes for welding the stay wires to the strand wires at their points of intersection. Beam 107 is then moved forward again to separate the two pairs of electrodes. At the same time, levers 131 start moving the picker frame upwardly in guide plate slots 123, as shown in Fig. 8. Due to the guide plates being in their forward position at this time, the picker fingers do not strike the cross wires that have been fed into the guide members in the meantime, but pass in front of the wires. After the picker fingers have risen above these cross wires, rods 136 move the guide plates back to their original position, shown in Fig. 6, in which the picker fingers are again directly above the cross wires and ready to move downwardly to grip those wires as soon as they have been severed by the cutters.

As soon as a pair of stay wires have been welded to the strand wires, feeding of the latter is resumed, whereby the welded stay wires are raised with the strand wires a predetermined distance to make way for the next set of stay wires which are about to be welded to the strand wires. When the spacing between the stay wires of the fence is to be the same as the distance between the cross

wires, the strand wires are moved upwardly twice that distance after each welding operation. This locates the lowest stay wire the same distance above the upper electrodes as the next bottom stay wire 87 will be below them, so the next top stay wire 86 will be half way between the stay wires 87 directly above and below it. On the other hand, if the spacing between fence stay wires is to be one-third the distance between the cross wires, for example, then the strand wires are moved upwardly two-thirds that distance each time. The upper electrodes will weld a stay wire half way between each preceding pair of stay wires, thereby making the space between the wires only one-third the distance between the upper and lower electrodes. Other spacing between the stay wires can be obtained in like manner by advancing the strand wires the proper amount, but care must be taken not to let the stay wires welded by the lower electrodes stop between the upper electrodes. Also, by making this machine larger, it is obvious that three or more stay wires can be welded simultaneously to the strand wires in the same manner as two are shown in the drawings.

A machine constructed in accordance with this invention can produce welded wire fence much faster than it has been made before because it can form a plurality of stay wires and weld them to the strand wires about as rapidly as earlier machines have been able to form a single stay wire and then weld it in place. When several stay wires are welded to the strand wires at the same time, a longer section of fence is thereby produced at that moment and a longer section of fence is moved forward after each welding operation than heretofore.

According to the provisions of the patent statutes, we have explained the principle and construction of our invention and have illustrated and described what we now consider to represent its best embodiment. However, we desire to have it understood that, within the scope of the appended claims, the invention may be practiced otherwise than as specifically illustrated and described.

We claim:

1. A wire fabric making machine, comprising means for intermittently and simultaneously feeding a plurality of parallel vertical strand wires lengthwise, means for intermittently and simultaneously feeding a plurality of vertically spaced horizontal wires across the front of the strand wires in spaced relation thereto, means for cutting said horizontal wires at one side of the strand wires while the horizontal wires are stationary to thereby form a set of stay wires in front of the strand wires, means for detachably gripping the set of stay wires and moving them rearwardly into contact with the strand wires, and horizontally movable welding electrodes for engaging the contacting strand and stay wires at their intersections when the strand wires are stationary to weld them together, said horizontal wire feeding means resuming the feeding of the horizontal wires before said gripping means leave said stay wires, and means for moving said gripping means forward away from the contacting strand and stay wires and vertically in front of the newly fed horizontal wires preparatory to engaging a new set of stay wires.

2. A wire fabric making machine, comprising means for intermittently and simultaneously feeding a plurality of parallel vertical strand wires lengthwise, means for intermittently and

simultaneously feeding a plurality of vertically spaced horizontal wires across the front of the strand wires in spaced relation thereto, means for cutting said horizontal wires at one side of the strand wires while the horizontal wires are stationary to thereby form a set of stay wires in front of the strand wires, pickers for moving the set of stay wires rearwardly into contact with the strand wires with each picker including vertically spaced wire-gripping fingers connected by an upright bar located in front of the forward position of the stay wires at all times, and welding electrodes for engaging the contacting strand and stay wires at their intersections when the strand wires are stationary to weld them together, said horizontal wire feeding means resuming the feeding of the horizontal wires behind said picker bars while said stay wires are gripped by the picker fingers.

3. A wire fabric making machine, comprising means for intermittently and simultaneously feeding a plurality of parallel vertical strand wires lengthwise, means for intermittently and simultaneously feeding a plurality of vertically spaced horizontal wires across the front of the strand wires in spaced relation thereto, means for cutting said horizontal wires at one side of the strand wires while the horizontal wires are stationary to thereby form a set of stay wires in front of the strand wires, pickers for moving the set of stay wires downwardly and rearwardly into contact with the strand wires with each picker including vertically spaced wire-gripping fingers connected by an upright bar located in front of the forward position of the stay wires at all times, horizontally movable welding electrodes for engaging the contacting strand and stay wires at their intersections when the strand wires are stationary to weld them together, and means for moving said picker bars forward away from the contacting strand and stay wires and then upwardly followed by a rearward movement to their original starting position, said horizontal wire feeding means resuming the feeding of the horizontal wires behind said picker bars while said stay wires are still gripped by the picker fingers.

4. A wire fabric making machine, comprising means for intermittently and simultaneously feeding a plurality of parallel vertical strand wires lengthwise, means for intermittently and simultaneously feeding a plurality of vertically spaced horizontal wires across the front of the strand wires in spaced relation thereto, means for cutting said horizontal wires at one side of the strand wires while the horizontal wires are stationary to thereby form a set of stay wires in front of the strand wires, pickers for moving the set of stay wires rearwardly into contact with the strand wires with each picker including vertically spaced wire-gripping fingers connected by an upright bar located in front of the forward position of the stay wires at all times, means for moving the picker bars first downwardly to engage said fingers with the stay wires and then downwardly and rearwardly toward the strand wires to place the stay wires against the strand wires, horizontally movable welding electrodes for engaging the contacting strand and stay wires at their intersections when the strand wires are stationary to weld them together, and means for then moving the picker bars forward away from the contacting strand and stay wires, said horizontal wire feeding means resuming the feeding of the horizontal wires behind said picker bars before the picker

fingers leave said stay wires, said first-mentioned picker moving means then moving the bars upwardly and forwardly and then upwardly, and said second-mentioned picker moving means then moving the bars rearwardly to position the picker fingers above said horizontal wires.

5. In a welded wire fence making machine in which horizontal stay wires are moved rearwardly toward vertically movable strand wires and then welded thereto, means for thus moving a plurality of vertically spaced stay wires simultaneously, said means comprising a plurality of horizontally spaced vertical bars, a plurality of vertically spaced gripping fingers pivotally connected to each bar and projecting rearwardly therefrom across the stay wires, means for moving said bars vertically to engage said fingers with the stay wires and then rearwardly to place the stay wires against the strand wires for welding, and means for moving said bars forward to separate said fingers from the stay wires, said bars then being returned to their original position.

6. In a welded wire fence making machine in which horizontal stay wires are moved rearwardly toward vertically movable strand wires and then welded thereto, means for thus moving a plurality of vertically spaced stay wires simultaneously, said means comprising a plurality of horizontally spaced vertical bars, a plurality of vertically spaced gripping fingers pivotally connected to each bar and projecting rearwardly therefrom across the stay wires, vertically spaced members connecting the upper and lower ends of said bars, means connected to one of said members for reciprocating it vertically to cause said fingers to periodically engage stay wires in their path, means for guiding said bars toward and away from the strand wires as the bars are reciprocated vertically, whereby said fingers place the stay wires against the strand wires for welding at their points of intersection, and means for reciprocating said bars horizontally to separate said fingers from the stay wires engaging the strand wires.

7. In a welded wire fence making machine in which horizontal stay wires are moved rearwardly toward vertically movable strand wires and then welded thereto, means for thus moving a plurality of vertically spaced stay wires simultaneously, said means comprising a plurality of horizontally spaced vertical bars, a plurality of vertically spaced gripping fingers pivotally connected to each bar and projecting rearwardly therefrom across the stay wires, vertically spaced members connecting the upper and lower ends of said bars, means connected to one of said members for reciprocating it vertically to cause said fingers to periodically engage stay wires in their path, means for guiding said bars toward and away from the strand wires as the bars are reciprocated vertically, whereby said fingers place the stay wires against the strand wires for welding at their points of intersection, and means connected to said guiding means for reciprocating them horizontally to separate said fingers from the stay wires engaging the strand wires.

8. In a welded wire fence making machine in which horizontal stay wires are moved rearwardly toward vertically movable strand wires and then welded thereto, means for thus moving a plurality of vertically spaced stay wires simultaneously, said means comprising a frame in front of the strand wires, a plurality of horizontally spaced vertical bars mounted in said frame, a plurality of vertically spaced gripping fingers carried by each bar and projecting rearwardly there-

11

from across the stay wires, guide members at the opposite ends of said frame provided with guide slots, means for reciprocating said members horizontally, said frame being provided with projections extending into said guide slots, and means connected to the frame for reciprocating it vertically, said slots in their rear position guiding said fingers into engagement with the stay wires and then rearwardly to transfer the stay wires to the strand wires for welding thereto, said guide members being moved forward after the stay wires have engaged the strand wires, and said slots and guide member reciprocating means then returning the frame to its original position.

9. In a welded wire fence making machine in which horizontal stay wires are moved rearwardly toward vertically movable strand wires and then welded thereto, means for thus moving a plurality of vertically spaced stay wires simultaneously, said means comprising a pair of vertically

spaced horizontal rods, vertical bars rigidly connecting the ends of said rods together, vertical guide plates disposed beside the outer surfaces of said end bars and each provided with a pair of vertically spaced slots, each slot having a vertical upper part and a downwardly and rearwardly inclined lower part, means projecting from said end bars into said slots for sliding movement lengthwise thereof, means for periodically moving said guide plates forwardly and rearwardly, means for periodically lowering and raising said rods and end bars as a unit relative to the guide plates, a plurality of vertical picker bars connected at their ends to said rods, and a plurality of vertically spaced picker fingers projecting rearwardly from each picker bar and adapted to temporarily grip said stay wires to move them downwardly and rearwardly into contact with the strand wires.
